UNITED STATES PATENT OFFICE.

HORACE E. NICHOLS, OF WHITESBORO, NEW YORK.

DESIGN FOR A CONTACT-POST FOR ELECTRIC SWITCHES.

SPECIFICATION forming part of Design No. 35,334, dated November 26, 1901.

Application filed October 24, 1901. Serial No. 79,876. Term of patent 7 years.

To all whom it may concern:

Be it known that I, HORACE E. NICHOLS, a citizen of the United States, residing at Whitesboro, in the county of Oneida and State of New York, have invented and produced a new and original Design for a Contact-Post for Electric Switches; and I do hereby declare the following to be a full, clear, and exact description of the same, reference being had to the accompanying drawings, forming a part thereof.

This invention relates to a new and original design for a contact-post for electric switches; and it consists of a shape and configuration as shown in the accompanying drawings and hereinafter described.

In the accompanying drawings, Figure 1 is a front elevation. Fig. 2 is a side elevation. Fig. 3 is an end elevation, and Fig. 4 is a plan view.

Referring to the drawings, 6 indicates a flat substantially rectangular-shaped base portion having perforations 7 and 7^a near its ends. Extending upwardly from the edges 25 of the base portion are two oppositely-dis-

posed members 8, bent so as to approach each other, but not meeting. In close proximity to one of the members 8 and separated therefrom by a narrow space 8^a is an upwardly-extending arm 9, the same being substantially parallel to the said member 8 for a portion of its length and then extending across to the plane of the other member 8 and terminating in a slight curve 10 a short distance above the end of the said member 8. 35

The essential features of the design are the base 6, having the upwardly-extending members 8, and the supplemental arm 9.

Having thus described the invention, what is claimed as new, and desired to be secured by Letters Patent, is—

The design for a contact-post for electric switches, substantially as shown and described.

In testimony whereof I affix my signature in presence of two witnesses.

HORACE E. NICHOLS.
